UNITED STATES PATENT OFFICE.

WILLIAM WILSON, JR., OF WATERBURY, CONN., ASSIGNOR TO THE BENEDICT & BURNHAM MANUFACTURING COMPANY, OF SAME PLACE.

IMPROVEMENT IN STOP-HINGES.

Specification forming part of Letters Patent No. 179,987, dated July 18, 1876; application filed July 1, 1876.

To all whom it may concern:

Be it known that I, WILLIAM WILSON, Jr., of Waterbury, in the county of New Haven and State of Connecticut, have invented a new Improvement in Stop Hinges; and I do hereby declare the following, when taken in connection with the accompanying drawings and the letters of reference marked thereon, to be a full, clear, and exact description of the same, and which said drawings constitute part of this specification, and represent, in—

Figure 1, an end view in the closed position; Fig. 2, the same in the open position; and in Fig. 3, a rear perspective view.

This invention relates to an improvement in that class of butt-hinges known to the trade as "stop-hinges"—that is to say, constructed so as to stop at a certain point in the opening; and the invention consists in the novel and peculiar construction of the stop, as herein-after described, and recited in the claim.

The two parts A and B of the hinge are constructed and united in substantially the usual manner, save that at one or both ends there is a recess formed at the center around the pintle, so as to form a shoulder, *a*, on one part, and *b* on the other. Into this recess the stop is placed. This stop consists of a disk, *d*, perforated at the center, and corresponding in general outline to the tubular part of the

hinge, the pintle extending through the stop, so as to be a means of securing this disk in place. The disk is constructed with two angular projections, *i*, arranged relatively to each other according to the extent the hinge is to be opened, (here represented as diametrically opposite.) Thus arranged, when the hinge is open the shoulders *a* and *b* strike the projections *i* on the collar, and thus form a bearing between the two parts, as seen in Fig. 2, which will prevent their being opened to a greater extent than that defined by the relative position of the said projections. These collars or stops are preferably arranged at both ends of the butt, as seen in Fig. 3, for the purpose both of symmetry and strength. One, however, will answer the purpose.

I claim—

The herein-described improvement in butt-hinges, consisting in a recess formed centrally between the two parts, combined with a perforated disk, *d*, in said recess, constructed with angular projections *i*, to take bearing on the shoulders *a* *b*, formed by the said recess, substantially as described.

WILLIAM WILSON, JR.
